JUNCTION BETWEEN SINGLE AND PUSH-PULL LINES

Nils E. Lindenblad, Rocky Point, N. Y., assignor
to Radio Corporation of America, a corporation
of Delaware

Application May 27, 1939, Serial No. 276,193

13 Claims. (Cl. 178—44)

The present invention relates to transmission lines and, more particularly, to a means for coupling a single line to a push-pull line or a pair of transmission lines operating in a push-pull relationship.

An object of the present invention is to provide a junction between a single and a push-pull line.

Another object of the present invention is to provide a transformer for coupling a single line to a push-pull line which will not unbalance either the single line or the push-pull line.

Still a further object of the present invention is to provide a transformer for coupling from a single to a push-pull line which maintains perfect balance over a wide frequency band.

Still a further object of the present invention is to provide a transformer for coupling from a single to a push-pull line which maintains perfect balance over a wide frequency band, or vice-versa.

My invention involves the connection of one of a pair of push-pull lines to one conductor of a single line and the other of the push-pull lines to the other conductor of the single line with means interposed between the push-pull lines and the single line for preventing any unbalancing effect upon the push-pull line from the connections of the single line.

My invention further contemplates the provision of means for counterbalancing any reactive components in the lines due to the connection between the single and push-pull lines.

Further objects and features of my invention will be readily apparent from the following detailed description which is accompanied by drawings in which Figure 1 illustrates an embodiment of the present invention; Figure 2 illustrates a modification of the form of my invention shown in Figure 1 in which certain reactive components are added for balance; Figure 3 illustrates still a further modification in which the reactive components are substantially completely compensated for; Figure 4 illustrates a further modification of my invention in which the reactive component due to the coupling between the single and push-pull line is prevented from affecting the single line, while Figure 5 illustrates a modification of Figure 4 particularly adapted to feed four transmission lines in a successive phase quadrature arrangement.

Referring, now, to Figure 1 I have shown a single concentric cable or transmission line composed of an outer sheath 6 and a central inner conductor 7. The outer sheath may be

grounded. I have also shown a pair of lines adapted to be fed in a push-pull relationship, one of said lines being composed of an outer sheath 8 and an inner conductor 9, and the other being composed of an outer sheath 10 and an inner conductor 11. The inner conductor 9 is directly connected to inner conductor 7 and is, therefore, energized in the same relationship as the conductor 7. The other inner conductor 11 is directly connected to the end of the sheath 10 of the single line and is therefore energized in phase opposition to the inner conductor 9. In order to completely uncouple the last quarter wave section of the single transmission line 6, 7 from the remainder of the same, I have provided an outer shell 12 surrounding sheath 6 of the single transmission line and connected thereto at a distance equal to a quarter of the operating wave length from the point of connection of conductor 11. The length of the conducting path within outer shell 12 and including the outer surface of the sheath 6 is of such length that the point of connection of conductor 11 is electrically freed from the outer conductor of the transmission line as far as ground potentials are concerned. This effect is due to the fact that the length of the conducting path discussed presents an extremely high impedance to the operating frequency of the apparatus at the point of attachment of conductor 11. Furthermore, no radiation can take place from the current flowing along the outer surface of sheath 6 since the current flowing along the inside of the outer shell 12 is equal and of opposite direction. Thus it will be seen that at the frequency for which the junction is designed the balanced push-pull line will not be subject to any unbalancing effects from the connections to the single lines, etc. This condition is, however, true only when the surrounded section of the single transmission line approximates a quarter of the length of the operating wave in length. If the frequency is changed or if the operating frequency is widely modulated some current will leak over the edge of the single transmission line sheath 6 and the push-pull output circuit will be unbalanced. In order to maintain perfect balance over a very wide frequency band I utilize the modification shown in Figure 2 in which I employ a second quarter wave conductor 23 arranged in an end-on relationship with the single line sheath 6 and surrounded by an outer shell 22. The center conductor 26, having the same diameter as the outer diameter of the sheath 6 of the single transmission line, is connected at one end 55

to the center conductor 7 of the single line and also to the center conductor 9 of one of the push-pull lines. The other end is electrically connected to the end of shell 22. With this construction it will be seen that looking from the push-pull line toward the junction along either conductor 9 or conductor 11 an exactly similar set of conditions is encountered. Therefore, for a wide frequency band or for frequencies varying widely from the frequency for which the junction is designed the reactive drain on conductor 11 due to an improper length of the surrounded portion of sheath 6 of the single transmission line is duplicated by an equal drain on conductor 9 by conductor 26. Since both lines 9 and 11 are connected through conductors 6, 26 to conductors 7, 6 of the single line, the current delivered by the single line results in perfectly balanced currents in the push-pull lines. Although the push-pull output remains balanced over a wide band of frequencies there is a reactive component produced causing reflection toward the source and the magnitude of this increases as the frequency departs from the frequency for which the junction was designed. It should be noted that this reflection takes place regardless of whether the energy feeds from push-pull to single line, or vice-versa.

In order to compensate for this effect I may use the modification of my invention shown in Figure 3. The construction of the left-hand portion of Figure 3 is exactly the same as described with reference to Figure 2. However, in each of the push-pull lines 8 and 10 at a distance equal to a quarter of the length of the operating wave from the junction I have provided balancing reactances. The theory of operation by which one insulator may compensate for the reactance introduced by an exactly similar one spaced therefrom a quarter wavelength has been discussed in some detail in a prior application by P. S. Carter, No. 112,037, filed November 21, 1936, and assigned to the assignee of the present application. The present invention applies a similar reasoning to the compensation of reactance introduced in a transmission line junction. The compensating reactance in line 8 is composed of outer shell 32 and center conductor 36. Center conductor 36 is connected at one end to conductor 9 and at the other end to shell 32. These elements are of the same physical dimensions as shell 22 and center conductor 26. Since all the physical dimensions are the same the reactances and resistance of both sections will be exactly the same and due to the quarter wave spacing each will compensate equally well for the other on each side of the midfrequency. For exact compensation at any particular side frequency the spacing will differ correspondingly from a quarter wave. Likewise, in line 10 of the balanced push-pull line I have provided a similar balancing reactance composed of outer shell 32' and center conductor 36' and connected in the same way as heretofore described.

While I have shown the outer shell 32 and 32' as being one continuous structure it is within the field of the present invention to make them entirely separate, if desired. However, from the standpoint of mechanical construction it is more desirable to make the two shell portions integral.

In Figure 4 I have shown a modification of the form of my invention shown in Figure 3 which is designed to supply a pair of lines in a phase quadrature relationship. This particular phase

relationship is desirable, for example, when energizing a turnstile antenna. This phase relationship is very simply provided for by including in transmission line 10 a phasing loop 40 having a length equal to a quarter of the length of the operating wave. This additional quarter wave length of the transmission line serves to delay the wave along the line an additional 90 electrical degrees, as clearly shown in Figure 4. Furthermore, in order to more completely counterbalance reactances, instead of having the single transmission line 6, 7 connected to the double line within shell 12, I have divided the single line into two branches, one of which is connected within outer shell 12 as before. The other branch 35' having an inner conductor 37' is substituted for the conductor 36' shown in Figure 3. It will be seen by following the connections from the junction of transmission line 6, 7 and connection 36', 37' around through the loop that each joint or connection is compensated by an exactly similar connection a quarter of the length of the operating wave away.

In Figure 5 I have shown a further development of the modification shown in Figure 4 which is particularly adapted to feed all four phases of a phase quadrature turnstile antenna. The structure for machine from a single to a push-pull line is the same as in previous figures, so it has not here been shown in detail. Each of the push-pull transmission lines 8 and 10 are arranged to energize two arms of a turnstile antenna by means of a pair of connections spaced a quarter of the length of the operating wave apart thus obtaining the phase quadrature relationship. For instance, connected to conductor 8 is a final transmission line 51 and at a distance a quarter of the length of the operating wave away a second line 54. Likewise, to transmission line 10 are connected transmission lines 52 and 53 spaced a quarter of the length of the operating wave apart. The resultant phase relationship of the four transmission lines is shown in the figure and should be obvious without further explanation. If similar radiating members are connected to each of the lines 51, 52, 53, 54, for any reflection back into line 8 from line 51 there is a similar reflection from line 54. The spacing between these lines being a quarter of the length of the operating wave, each reflection compensates for the other and there is very little final resultant effect in line 8. A similar situation, of course, likewise exists with respect to lines 52 and 53 and their connection to transmission line 10. Throughout the present application where I refer to the operating frequency with respect to a wide band system it is to be understood that the midband frequency is considered.

While I have particularly shown and described several modifications of my invention, it is to be distinctly understood that my invention is not limited thereto but that improvements within the scope of the invention may be made.

I claim:

1. In combination, a single transmission line having an outer sheath and an inner conductor and a push-pull pair of balanced transmission lines, a connection from the inner conductor of said single line to a conductor of one of said push-pull lines, a connection from the sheath of said single line to a conductor of the other of said push-pull lines, an outer shell surrounding the end portion of said single line, said shell being connected to said sheath at a distance equal to a quarter of the length of the operating wave.

- from the end of said single line, and a balancing circuit including an inner conductor connected to the inner conductor of said single line and having a diameter equal to the diameter of the outer sheath of said single line and an outer shell having a diameter equal to the diameter of the first outer shell and connected thereto, the inner conductor and outer shell of said balancing circuit being connected together at a distance 5 equal to a quarter of the length of the operating wave from said connections.
2. In combination, a single transmission line having an outer sheath and an inner conductor and a pair of balanced transmission lines, a connection from the inner conductor of said single line to a conductor of one of said pair of lines, a connection from the sheath of said single line to a conductor of the other of said pair of lines, an outer shell surrounding the end portion of 10 said single line, said shell being connected to said sheath at a distance equal to a quarter of the length of the operating wave from the end of said single line, a balancing circuit including an inner conductor connected to the inner conductor of said single line and having a diameter equal to the diameter of the outer sheath of said single line and an outer shell having a diameter equal to the diameter of the first outer shell and connected thereto, the inner conductor and outer shell of said balancing circuit being connected together at a distance equal to a quarter of the length of the operating wave from said connections, and a compensating circuit similar to 15 said balancing circuit connected to each of said pair of push-pull lines at a distance equal to a quarter of the length of the operating wave from said junction whereby the reactance of said junction is compensated.
3. Means for coupling a single concentric line having an outer sheath and an inner conductor to a push-pull pair of concentric transmission lines each having an outer sheath and an inner conductor comprising a connection from the inner conductor of said single line to an inner conductor of one of said pair of lines, a connection from the end of the sheath of said single line to the inner conductor of the other of said pair of lines, an outer shell surrounding the end of said single lines and its junction with said pair of lines, said shell being connected to the outer sheath of said single line at a distance equal to a quarter of the length of the operating wave from the end of said sheath, and a balancing circuit including an inner conductor having a 20 diameter equal to the diameter of the outer sheath of said single line connected to the inner conductor of said single line and an outer shell having a diameter equal to the diameter of the first outer shell and connected thereto, the inner conductor and outer shell of said balancing circuit being connected together at a distance equal to a quarter of the length of the operating wave from said connections, and a compensating circuit similar to said balancing circuit connected to each of said pair of lines at a distance equal to a quarter of the length of the operating wave from said junction whereby the reactance of said junction is compensated.
4. Means for coupling a single concentric line having an outer sheath and an inner conductor to a push-pull pair of concentric transmission lines each having an outer sheath and an inner conductor comprising a connection from the inner conductor of said single line to an inner conductor of one of said pair of lines, a connection from the end of the sheath of said single line to the inner conductor of the other of said pair of lines, an outer shell surrounding the end of said single lines and its junction with said pair of lines, said shell being connected to the outer sheath of said single line at a distance equal to a quarter of the length of the operating wave from the end of said sheath, and a balancing circuit including an inner conductor having a 25 diameter equal to the diameter of the outer sheath of said single line connected to the inner conductor of said single line and an outer shell having a diameter equal to the diameter of the first outer shell and connected thereto, the inner conductor and outer shell of said balancing circuit being connected together at a distance equal to a quarter of the length of the operating wave from said connections, and a compensating circuit similar to said balancing circuit connected to each of said pair of lines at a distance equal to a quarter of the length of the operating wave from said junction whereby the reactance of said junction is compensated.
5. Means for coupling a single concentric line having an outer sheath and an inner conductor to a push-pull circuit having a pair of conductors adapted to be energized in an opposing phase relationship comprising a connection from said inner conductor to one of said pair of conductors, a connection from the end of said outer sheath to 30 the other of said pair of conductors and an outer shell surrounding the end of said single line and its junction with said pair of lines, said shell being connected to said outer sheath at a distance equal to a quarter of the length of the operating wave from the end of said sheath, and a balancing circuit including an inner conductor having a diameter equal to the diameter of the outer sheath of said single line connected to the inner conductor of said single line and an outer shell 35 having a diameter equal to the diameter of the first outer shell and connected thereto, the inner conductor and outer shell of said balancing circuit being connected together at a distance equal to a quarter of the length of the operating wave from said connections, and a compensating circuit similar to said balancing circuit connected to each of said pair of lines at a distance equal to a quarter of the length of the operating wave from said junction whereby the reactance of said junction is compensated.
6. Means for coupling a single concentric transmission line having an outer sheath and an inner conductor to a push-pull pair of concentric transmission lines each having an outer sheath and an inner conductor, said single line being branched into two branches, one of said branches being a quarter of the length of the operating wave longer than the other of said branches, said means comprising a connection from the inner conductor of one of said pair of lines to each of the inner conductors of said branches, a connection from the inner conductor of the other of said pair of lines to the end of the outer sheath of each of said branches, an outer shell surrounding the end of each branch of said single line, said shells being connected to the outer sheath and said branches at a distance equal to a quarter of the length of the operating wave from the end of each branch, said outer shell extending beyond the ends of said branches, and an inner conductor within the extending portion of said shells having a diameter equal to the diameter of the outer sheath of said single line connected to the inner conductors of said branches, each of said outer shells and said last mentioned inner conductors being connected together a distance equal to a quarter of the length of the operating wave beyond the point of connection to said inner conductors.
7. Means for coupling a single concentric line having an outer sheath and an inner conductor to a push-pull pair of concentric transmission lines each having an outer sheath and an inner conductor comprising a connection from the inner conductor of said single line to an inner conductor of one of said pair of lines, a connection from the end of the sheath of said single line to the inner conductor of the other of said pair of lines, an outer shell surrounding the end of said single lines and its junction with said pair of lines, said shell being connected to the outer sheath of said single line at a distance equal to a quarter of the length of the operating wave from the end of said sheath, and a balancing circuit including an inner conductor having a diameter equal to the diameter of the outer sheath of said single line connected to the inner conductor of said single line and an outer shell having a diameter equal to the diameter of the first outer shell and connected thereto, the inner conductor and outer shell of said balancing circuit being connected together at a distance equal to a quarter of the length of the operating wave from said connections, and a compensating circuit similar to said balancing circuit connected to each of said pair of lines at a distance equal to a quarter of the length of the operating wave from said junction whereby the reactance of said junction is compensated.

- conductor of one of said pair of lines, a connection from the end of the sheath of said single line to the inner conductor of the other of said pair of lines, an outer shell surrounding the end of said single lines and its junction with said pair of lines, said shell being connected to the outer sheath of said single line at a distance equal to a quarter of the length of the operating wave from the end of said sheath, and a balancing circuit including an inner conductor having a diameter equal to the diameter of the outer sheath of said single line connected to the inner conductor of said single line and an outer shell having a diameter equal to the diameter of said first outer shell and connected thereto, the inner conductor and outer shell of said balancing circuit being connected together at a distance equal to a quarter of the length of the operating wave from said connections, and a compensating circuit having an impedance equal to that of said balancing circuit connected to each of said pair of push-pull lines at a distance equal to a quarter of the length of the operating wave from said junction whereby the reactance of said junction is compensated.
25. 8. Means for coupling a single concentric line having an outer sheath and an inner conductor to a push-pull circuit having a pair of conductors adapted to be energized in an opposing phase relationship comprising a connection from said inner conductor to one of said pair of conductors, a connection from the end of said outer sheath to the other of said pair of conductors and an outer shell surrounding the end of said single line, said shell being connected to said outer sheath at a distance equal to a quarter of the length of the operating wave from the end of said sheath, and a balancing circuit including an inner conductor having a diameter equal to the diameter of the outer sheath of said single line connected to the inner conductor of said single line and an outer shell having a diameter equal to the diameter of said first outer shell and connected thereto, the inner conductor and outer shell of said balancing circuit being connected together at a distance equal to a quarter of the length of the operating wave from said connections.
9. A concentric transmission line circuit comprising a single concentric transmission line having an outer sheath and an inner conductor to a push-pull pair of concentric transmission lines each having an outer sheath and inner conductor, said inner conductor being branched into two branches, one of said branches being a quarter of the length of the operating wave longer than the other of said branches, a connection from the inner conductor of one of said pair of lines to each of the inner conductors of said branches, a connection from the inner conductor of the other of said pair of lines to the end of the outer sheath of each of said branches, an outer shell surrounding the end of each branch of said single line, said shell being connected to the outer sheath of said branches at a distance equal to a quarter of the length of the operating wave from the end of each branch, said outer shell extending beyond the ends of said branches, and the inner conductor having a diameter equal to the diameter of the outer sheath of said single line connected to the inner conductors of said branches, each of said outer shells and said last mentioned inner conductors being connected together a distance equal to a quarter of the length of the operating wave beyond the point of connection to said inner conductors, each of said push-pull pair of lines being divided into two branches, one branch of

each being a quarter of the length of the operating wave longer than the other, whereby four phase output is obtained.

10. Means for coupling over a wide band of frequencies a single concentric line having an outer sheath and an inner conductor to a push-pull circuit having a pair of conductors adapted to be energized in an opposing phase relationship comprising a connection from said inner conductor to one of said pair of conductors, a connection from the end of said outer sheath to the other of said pair of conductors and an outer shell surrounding the end of said single line, said shell being connected to said outer sheath at a distance from the end of said sheath equal to a quarter wavelength at midband frequency, the surrounded portion of said outer sheath introducing at frequencies removed from said midband an undesired reactive effect into one of said pair of conductors and an exactly similar reactance connected to the end of the other of said pair of conductors whereby said push-pull circuit remains balanced over said wide band.

11. Means for coupling over a wide band of frequencies a single concentric line having an outer sheath and an inner conductor to a push-pull circuit having a pair of conductors adapted to be energized in an opposing phase relationship comprising a connection from said inner conductor to one of said pair of conductors, a connection from the end of said outer sheath to the other of said pair of conductors and an outer shell surrounding the end of said single line, said shell being connected to said outer sheath at a distance from the end of said sheath equal to a quarter wavelength at midband frequency, the surrounded portion of said outer sheath introducing at frequencies removed from said midband an undesired reactive effect into one of said pair of conductors and an exactly similar reactance connected to the end of the other one of said pair of conductors at a quarter wavelength distance from its end.

12. Means for coupling over a wide band of frequencies a single concentric line having an outer sheath and an inner conductor to a push-pull circuit having a pair of conductors adapted to be energized in an opposing phase relationship comprising a connection from said inner conductor to one of said pair of conductors, a connection from the end of said outer sheath to the other of said pair of conductors and an outer shell surrounding the end of said single line, said shell being connected to said outer sheath at a distance from the end of said sheath equal to a quarter wavelength at midband frequency, the surrounded portion of said outer sheath introducing at frequencies removed from said midband an undesired reactive effect into one of said pair of conductors, an exactly similar reactance connected to the end of the other of said pair of conductors to compensate for said reactive effect and further similar reactances connected to each of said pair of conductors at a quarter wavelength distance from their ends, each of said reactances comprising a quarter wave section of transmission line.

13. Means for coupling over a wide band of frequencies a single concentric line having an outer sheath and an inner conductor to a push-pull circuit having a pair of conductors adapted to be energized in an opposing phase relationship comprising a connection from said inner conductor to one of said pair of conductors, a connection from the end of said outer sheath to the other of said pair of conductors and an outer shell surrounding

- the end of said single line, said shell being connected to said outer sheath at a distance from the end of said sheath equal to a quarter wavelength at midband frequency, the surrounded portion of said outer sheath introducing at frequencies removed from said midband an undesired reactive effect into one of said pair of conductors, an exactly similar reactance connected to the end of the other of said pair of conductors to compensate for said reactive effect and further similar reactances connected to each of said pair of conductors at a quarter wavelength distance from their ends, each of said reactances comprising a quarter wave section of transmission line, 5 said sections of transmission line being shorted at the ends remote from their connections to said pair of conductors.

NILS E. LINDENBLAD.
